UNITED STATES PATENT OFFICE

136,158

DESIGN FOR A DISPLAY RACK FOR BELTS OR THE LIKE

William L. Burkhard, Denver, Colo., assignor to The Gates Rubber Company, Denver, Colo., a corporation of Colorado

Application June 14, 1943, Serial No. 110,455

Term of patent 14 years

To all whom it may concern:

Be it known that I, William L. Burkhard, a citizen of the United States, residing at the city and county of Denver and State of Colorado, have invented a new, original, and ornamental Design for a Display Rack for Belts or the like, of which the following is a specification, reference being had to the accompanying drawing, forming part thereof.

In the drawing the figure is a perspective view of a display rack for belts or the like, showing my design.

I claim:

The ornamental design for a display rack for belts or the like, as shown.

WILLIAM L. BURKHARD.
